UNITED STATES PATENT OFFICE.

AXEL A. STROM, OF AUSTIN, ILLINOIS.

METHOD OF FORMING A RAIL-BRACE FROM T-METAL.

SPECIFICATION forming part of Letters Patent No. 380,668, dated April 3, 1888.

Application filed January 30, 1888. Serial No. 262,410. (No model.).

To all whom it may concern:

Be it known that I, AXEL A. STROM, a citizen of the United States, residing at Austin, in the county of Cook and State of Illinois, have 5 invented a new and useful Improvement in the Method of Forming a Rail-Brace from T-Metal, of which the following is a specification.

My invention relates to an improvement in the manufacture of rail-braces made from 10 blanks composed of sections of T-rails, the article being the result of one of several ways of utilizing refuse rail-sections or T-rails which have been worn out.

Of the various forms of rail-braces produced 15 by manipulating T-rails into different shapes two are known to me as having been used practically, one being formed by adapting the rail flange or base to fit the head of the rail to be braced and drawing out the rail-head of the 20 blank to form with the web portion thereof the foot or shank of the brace, the shank being curved to produce an upward convexity, whence the foot portion tends with a downward curvature to fit the tie to which it is to be secured

25 by spikes passed through spike-holes provided toward the end of the foot portion. The other form referred to is produced by bending one side or wing of the flange or base of the blank to form as an extension of the web the foot portion 30 of the brace and adapt it to fit upon the tie to which it is to be secured in the manner stated of the first of the two braces herein described, and the opposite wing of the flange is bent toward the head of the T-blank to brace

35 it, the latter being previously bent over toward the bracing portion and adapted to fit against the web and between the head and flange of the rail to be braced. The use of each of these braces is attended with objections incident to 40 its construction. That first described has attenuated bearing-surfaces at the opposite extremities of its head portion respectively in contact with the under side of the head and upper side of the flange of the rail it braces, and affords

45 insufficient resistance to the strain against the rail, whereby the shank is bent from its normal shape, thus separating the head of the brace from the rail and destroying the bracing function of the brace, and frequently also fracturing 50 the brace through the curved shank portion.

The second of the two braces described is rendered too weak to bear the strain exerted upon the rail it braces by the bending of the flange in the opposite directions described to produce the foot portion and prop or re-enforcing 55 agent of the head portion, as it breaks readily through the shank more or less toward the foot portion, and quite commonly at the line of bending the flange.

My object is to provide a form of rail-brace 60 constructed from a T-rail blank which shall be devoid of the defects incident to the constructions set forth; and to this end my invention consists in the method of forming a rail-brace from a T-metal blank which consists in 65 bending the web portion to form the shank of the brace and bending the wings of the base or flange toward each other to produce a continuation of the web or shank and form the foot portion. 70

The construction produced by my improved method is shown in the accompanying drawings, in which—

Figure 1 is a perspective view of the brace; Fig. 2, a side view of the same in operative 75 position against a section of rail; and Fig. 3, a similar view broken and showing a modification as to the manner of forming the head of the brace, the dotted lines showing the original and the full lines the upset head. 80

A is the rail-brace, comprising a head portion, *r*, corresponding with the head of the section of T-metal blank from which it is formed, a shank, *q*, slightly curved, as shown, and formed of the web portion of the blank, and a foot 85 portion, *p*, formed of the flange of the blank by bending the wings thereof toward and into contact with each other and welding them together, whereby they produce a continuation of the shank and adapted to fit upon the tie to 90 which the foot portion is spiked or bolted, the spikes or bolts being commonly driven through holes provided to admit them in the foot portion.

If the space between the head and flange of 95 the T-rail to be braced be wider than the head of the blank from which the brace is formed, as may occur, the brace-head may be upset to fit the space with the desired snugness, as shown in Fig. 3. The rail-brace thus has a 100

head of the full dimensions, or substantially so, of the head of the blank, thereby presenting such wide bearing-surfaces against the head and flange of the rail it braces that it takes up 5 a very material portion of the strain exerted against the rail, and consequently reducing that which would otherwise be transmitted to the shank and foot portions, the former of which is so slightly curved or bent as to resist great 10 strain tending to bend it. The foot portion p , being composed of the double thickness of the web of the T-blank, adds especially material strength to the brace, since the manner of bending it—that is, to form a continuation of 15 the web forming the shank portion q —does not weaken it at the bending line, while the duplicate form of the foot portion adds materially to the strength.

What I claim as new, and desire to secure 20 by Letters Patent, is—

1. The method of forming a rail-brace from a T-metal blank which consists in bending the web portion to form the shank of the brace and bending the wings of the base or flange toward each other to produce a continuation of the 25 web or shank and form the foot portion, substantially as described.

2. The method of forming a rail-brace from a T-metal blank which consists in upsetting the head of the blank to cause it to fit between 30 the head and flange of the rail to be braced, bending the web portion to form the shank of the brace and bending the wings of the base or flange toward each other to produce a continuation of the web or shank and form the foot 35 portion, substantially as described.

AXEL A. STROM.
